UNITED STATES PATENT OFFICE.

GRANDISON T. ROGERS, OF JEFFERSON CITY, MISSOURI.

LOCK.

SPECIFICATION forming part of Letters Patent No. 447,623, dated March 3, 1891.

Application filed April 26, 1890. Serial No. 349,595. (Model.)

To all whom it may concern:

Be it known that I, GRANDISON T. ROGERS, of Jefferson City, in the county of Cole and State of Missouri, have invented a new and Improved Lock, of which the following is a full, clear, and exact description.

The object of the invention is to provide a new and improved lock which is simple and durable in construction, and is arranged in such a manner that it is impossible to unlock it from one side when it has been locked on the other side.

The invention consists of a bolt fitted to slide and provided with notches, and a spring-pressed lever adapted to engage the said notches and operated on by the key in conjunction with the bolt.

The invention also consists in certain parts and details and combinations of the same, as will be described hereinafter, and then pointed out in the claims.

Reference is to be had to the accompanying drawings, forming a part of this specification, in which similar letters of reference indicate corresponding parts in all the figures.

Figure 1 is a face view of the lock with the cover-plate removed. Fig. 2 is an inside face view of the cover-plate. Fig. 3 is an inverted sectional plan view of the improvement on the line xx of Fig. 1. Fig. 4 is a similar view of the same on the line yy of Fig. 1. Fig. 5 is a sectional plan view of the same on the line zz of Figs. 1 and 2. Fig. 6 is a perspective view of the latch, and Fig. 7 is a perspective view of the bolt.

The improved lock A is provided with a suitable casing B, adapted to be covered by a cover-plate C, fastened to the casing by suitable bolts or other means. In the casing B is fitted to slide the locking-bolt D, supported at its inner end on a pin E, projecting from the casing and passing through a longitudinal slot D' in the said bolt. On the under side of the bolt D are formed the V-shaped notches F and F', into which is adapted to pass the bit of the key, which may be inserted from the inside of the door on which the lock is applied through a key-hole G, formed in the cover-plate C, or the said key may be inserted from the outside through a key-hole G', formed in the casing B, the two key-holes G and G' be-

ing arranged suitable distances apart and in line with the notches F and F', respectively. The bit of the key is also adapted to operate on the under side of a lever H, extending through a vertical slot D^2 , formed in the bolt D, as is plainly illustrated in Fig. 7. The lever H is fulcrumed at H' to the casing B, and is provided with a lug H ^{2} , adapted to engage alternately notches D ^{3} and D ^{4} , formed on the top of the lever D. The lever H is also pressed downward by a spring I, so as to hold the lug H ^{2} firmly in engagement with the respective notch D ^{3} or D ^{4} . The lever H extends across the notches F and F', so as to be engaged at its under side by the bit of the key when the latter operates on the bolt in either of the said notches, as hereinafter more fully described. When the key is introduced into the casing B through the key-hole G in the cover plate C, then the bit of the key passes into a rectangular aperture formed in a vertically-arranged plate J, fitted to slide in suitable guideways K', formed on a plate K, fitted to slide longitudinally in suitable bearings B', formed on the casing B, and on a lug B ^{2} , extending inward from the casing B and engaging a slot in the plate, said lug being provided with a round aperture B ^{4} to receive the inner end of the key-shank. The plate K is provided with a key-hole K ^{2} , adapted to connect with or disconnect from the key-hole G', formed in the back of the casing B.

On the lower end of the plate J, previously mentioned, is formed a lug J', adapted to engage alternately the notches N' and N ^{2} formed in a bar N, secured to the inside of the casing B, the lug J' of the said plate J being pressed into contact with either of the said notches by means of a spring L, secured to the plate K and pressing with its free end on a pin J ^{2} , projecting from the plate J. A similar arrangement to the one just described is formed on the inside of the cover-plate C—that is, a plate O is provided which is fitted to slide vertically in suitable bearings P', formed in a plate P, constructed similarly to the plate K, and mounted to slide on suitable bearings C', fastened or formed on the inside of the cover-plate C, and on a lug C ^{2} on the plate C engaging a slot in the plate and provided with a round aperture C ^{3} to receive the end

of the key-shank. The plate O is provided with a rectangular aperture, into which is adapted to pass the bit of the key when the latter is inserted through the key-holes G' and K² to operate on the bolt D in the notch F'.

On the lower end of the plate O is formed the lug O', adapted to engage alternately the notches Q' and Q², formed in the bar Q, secured to the inside of the cover-plate C, being similar to the bar N, previously mentioned. A spring L', held on the plate P, presses on a pin O², projecting from the plate O. (See Fig. 2.)

In the plate P is formed a key-hole P², adapted to connect with or disconnect from the key-hole G, formed in the cover-plate C, and previously mentioned. The positions of the two plates K and P are such that when the bolt D is in an outermost position the key-hole of one of the said plates registers with its respective key-hole and the other is disconnected from its key-hole, and vice versa.

In the upper part of the casing B is fitted to slide a latch R, which is made reversible, and which is for this purpose provided in its shank R' with oppositely-arranged notches R² and R³, forming a double-head R⁴. (See Fig. 6.) The latter is adapted to engage a recess S' in the head S, secured on the bars S², connected with each other at their rear end by a flange S³, operated on by the tumbler T, through which passes the usual door-knob shaft T' for turning the said tumbler. A pin S⁴ projects from the head S and passes through a bearing B³, projecting from the casing B. A spring S⁵ is coiled on the said pin S⁴ and rests with one end against the said bearing B³ and its other end against the said head S, so as always to hold the latch R in an outermost position, unless the said latch is pressed inward by the turning of the door-knob in the usual manner, so as to compress the spring S⁵. When the pressure on the door-knob is released, the compressed spring S⁵ forces the latch to its outermost position again. The head S is fitted to slide between a movable block U and a stationary block V, secured to the casing B. The movable block U fits onto the top of the head S and is provided with a pin U', passing through a longitudinal slot B⁵, formed in the top of the casing B, as is plainly shown in Fig. 3.

On the outside of the pin U' is arranged a button U² for conveniently moving the block U forward or backward to uncover the top of the head S, so as to remove the latch R from the said head in order to turn it over when it is desired to reverse the latch R. When the latter has been accomplished, the block U is again moved to its position, so as to hold the head R⁴ in engagement with the head S.

The operation is as follows: As shown in Fig. 1, the bolt D is in an innermost position and the door is unlocked, except by the latch R, in the usual manner. When the bolt is in this position, the key-hole G in the cover-plate C registers with the key-hole P² in the

plate P, and the key-holes K² and G' also register with each other. When an operator on the inside of the door desires to lock the door, the key is inserted through the key-holes G and P² and turned so that the bit of the key first raises the lever II, so as to disconnect its lug II² from the notch D³. Then the bit of the key passes against the left edge of the notch F and shifts the bolt D into an outermost position, locking the door. At the same time the bit of the key acts on the plate J, so as to first raise the latter with its lug J' out of contact with the notch N², and then by the bit of the key acting against the side of the said plate J pushes the entire plate K to the left, so that the key-hole K² is disconnected from the key-hole G', as shown in Fig. 5, and the plate J again slides downward to engage with its lug J' the notch N' by the action of the spring L. Now a key cannot be inserted from the outside of the door, as the key-hole G' is closed. In order to unlock the door from the inside, the operator again inserts the key in the key-holes G and P² and turns the key in an opposite direction, so that the lever II is first swung upward, the bolt D is shifted inward until the lug II² again drops into the notch D³, and at the same time the plate J is raised and the plate K shifted to the right, so that the key-hole K² again registers with the key-hole G' in the casing B. The plate K, with the plate J, is again locked in place by the lug J' engaging the notch N². Now when the operator desires to lock the door from the outside he inserts the key through the key-holes G' and K², turns the key so that the bit of the key passes into the notch F' and raises the lever II to unlock the bolt D, which by the bit of the key engaging the left side of the notch F' causes the bolt D to slide outward. The lug II² then drops into the notch D⁴ and locks the bolt in place. At the same time the bit of the key acts on the plate O, so as to raise the latter in order to disconnect its lug O' from the notch Q², after which the movement of the bit pressing against one side of the plate O shifts the plate P to the left and the key-holes P² and G are disconnected. The lug O' then drops into the notch Q' and the plate P is locked. It will be seen that as the key-hole G is now covered up a key cannot be inserted into the lock from the inside of the door.

Having thus described my invention, what I claim as new, and desire to secure by Letters Patent, is—

1. In a lock, the combination, with a casing having a key-hole and a cover for the said casing having a key-hole, the said key-holes not being in line with each other, of plates fitted to slide in the said casing and on the said cover, each provided with a key-hole adapted to register with its respective key-hole in the said casing or cover, and a bolt fitted to slide in the said casing and provided with notches adapted to be engaged by the bit of the key,

which is also adapted to operate the said plates to shift the latter longitudinally, and a spring-pressed locking-plate held to slide vertically in the said plates, substantially as shown and described.

2. In a lock, the combination, with a plate provided with a key-hole and fitted to slide longitudinally, of a second plate fitted to slide vertically in the said first-named plate and provided with an aperture adapted to be engaged by the bit of the key, and means, substantially as described, for locking the said vertically-sliding plate in position, as set forth.

3. In a lock, the combination, with a plate having a key-hole and fitted to slide longitudinally, of guideways arranged vertically on the said plate, an apertured plate fitted to slide vertically on the said first-named plate and adapted to be acted on by the bit of the

key, a notched bar, and a spring held on the said first-named plate and pressing on the said second-named plate to engage the latter alternately with notches in the said bar, substantially as shown and described.

4. In a lock, the combination of a latch having a notched shank, a spring-pressed and sliding head having its upper face recessed to receive the notched shank of the latch, and a sliding block above the head and covering the recess thereof, the said block serving as one of the guides for the head and adapted to be operated from the outside to permit the latch to be reversed, substantially as described.
